ALEXANDER T. DRYSDALE, OF BURLINGTON, NEW JERSEY.

MACHINE FOR STAMPING SAND MOLDS.

1,154,238.

Specification of Letters Patent. Patented Sept. 21, 1915.

Application filed June 5, 1915. Serial No. 32,412.

To all whom it may concern:

Be it known that I, ALEXANDER T. DRYSDALE, a citizen of the United States, residing at Burlington, in the county of Burlington 5 and State of New Jersey, have invented a new and useful Machine for Stamping Sand Molds, of which the following is a specification.

In the manufacture of cast iron pipe, such 10 as water or gas mains, it is desirable, and sometimes necessary, to have various lettering cast on the pipe in raised letters, such as the name of the manufacturer, the year in which the pipe is cast, the name of the 15 customer, and the consecutive number of the pipe.

At present, this lettering is done by hand, the individual letters being mounted on 20 wooden blocks, and the letters being separately stamped into the mold by pressing these wooden blocks against the sand manually. This is not only troublesome, but does not produce good results, as by reason 25 of the carelessness of the molders the lettering may be crooked, the depth of the letters may lack uniformity, and the whole legend may sometimes be entirely illegible. Sometimes this results in the rejection of the pipe by the inspector, and such rejections are 30 sometimes so frequent as to cause serious trouble, delay, and loss.

It is the object of my present invention to provide a machine which will stamp all the letters at one time, and will insure their being 35 perfectly aligned and perfectly legible, and by which the letters may be made of any desired depth and all of uniform depth.

In carrying out my invention I provide a main body which is sufficiently small so that 40 it can be inserted in the mold and which carries any number of radially movable letter blocks, on which are mounted the desired letters. These letter blocks are spring-pressed inward, but may be moved outward 45 by air pressure, which is supplied to the interior of the body to act against the inner surfaces of the letter blocks. In order to lessen the machine work, there is preferably provided an air bag of some flexible mate- 50 rial within the body, the air pressure being supplied to the interior of this bag and the exterior thereof bearing against the letter blocks. The body is also made in a plurality of parts, which are acted against by the 55 same air bag so that these parts are spread to engage the mold walls before the letter

blocks are moved radially to force the letters into the mold.

The accompanying drawings illustrate my invention.

Figure 1 is a vertical central section through a mold showing my improved mold stamping machine in place therein; Fig. 2 is a vertical section through the mold stamping machine, on a slightly larger scale than Fig. 1, 60 being taken substantially on the line 2—2 of Fig. 4 and showing the letter blocks forced outward; Fig. 3 is a plan of the mold stamping machine shown in Fig. 2; Fig. 4 is a section on the line 4—4 of Fig. 2; Fig. 5 is 65 a perspective view of one of the letter blocks; and Fig. 6 is a perspective view of one of the letter type which are removably mounted in the letter blocks.

The mold stamping machine has a hollow 75 substantially cylindrical body which is made in a plurality of parts. As shown, there are two mating parts 10 and 11, which are substantially semi-cylindrical in shape, with inwardly projecting flanges 12 at their ends, to 80 form the end closing plates of the hollow cylinder. The two parts 10 and 11 are connected by aligned hinges 13 at one side so that they can have a slight opening and closing movement relative to each other. A 85 tension spring 14 tends to draw the two parts 10 and 11 together about the hinges 13. The joint between the parts 10 and 11 opposite the hinges 13 is covered by a lap strip 23, to keep sand out of the inside of 90 the body. The surfaces of the parts 10 and 11 are cut away from and within the true cylindrical form as they approach their meeting plane, to provide for clearance 95 when inserting the machine into and removing it from the mold.

Each of the parts 10 and 11 has one or more longitudinal openings 15 in its walls, which openings extend nearly to both ends, and in these openings are mounted radially 100 movable letter blocks 16. These letter blocks are of the form shown in Fig. 5, with a main portion slidably fitting in the opening 15, a pair of lateral flanges 17 near their inner surface for limiting the outward movement 105 of the letter blocks by engaging the walls of the members 10 or 11, and a dove-tailed slide-way 18 in its exterior face. This dove-tailed slide-way 18 is closed at the lower end, but is open and partly cut away at the upper end 110 to allow the insertion and removal of the type blocks 19, which slidingly fit in such

dove-tail slideway and have exterior faces which are curved to fit the mold wall and bear raised letters 20. Ordinarily, there is but one letter on each type block. By this 5 construction the type in the different letter blocks may be changed without removing the letter blocks from the body portion. The letter blocks have leaf springs 21 attached to them for bearing against the inside wall 10 of the members 10 and 11 and tending to draw the letter blocks 16 inward so that the outer surfaces of the letters 20 will be inside of the cylindrical form of the outer walls of the parts 10 and 11, for purposes herein- 15 after apparent. The inward movement of the letter blocks 16 is limited by the heads of guide screws 22.

Within the hollow body formed by the parts 10 and 11 is an air bag 25, of any suitable flexible material, such as rubber. This bag rests against the inner surfaces of the letter blocks 16, which are slightly concave to receive it, and also against intermediate supports 26 between adjacent letter blocks 25 16. The ends of the air bag 25 are provided by a plate 27, preferably of metal, at the bottom and a plate 28, also preferably of metal at the top. The plate 28 has a central boss which is threaded to receive the lower 30 end of a pipe 29, which also extends through a central boss 30 on the end plate 12 of the member 10, the interfitting end plate 12 on the member 11 being hollowed out to fit around such boss 30. A lock nut 31 may 35 be mounted on the pipe 29 above the boss 30. The pipe 29 forms both the support for the machine and a supply pipe for the air. It is provided at the desired distance above the machine with a pair of cross arms 32, for 40 engaging the top of the mold and thus fixing the depth to which the stamping machine is lowered into the mold. At its upper end the pipe 29 leads into a three-way valve 33, which on one side is connected by a rubber 45 hose 34 to any suitable source of air pressure and at the other is connected to an upwardly turned L 35 for discharging into the atmosphere.

In operation, the sand mold 40 is formed 50 in the flask 41 in any ordinary or convenient manner. When the mold has been formed ready for lettering, my improved mold stamping machine is lowered into the mold, until the arms 32 strike the top of the mold, 55 as shown in Fig. 1. While the mold stamping machine is thus being lowered, the interior of the air bag 25 is connected to the atmosphere so that the springs 21 hold the letter blocks 16 inward and the spring 14 60 holds the two parts 10 and 11 drawn together. When the mold stamping machine has been lowered into place, the desired lettering being of course arranged in the letter block 16 before lowering it, the valve 33 is 65 turned to admit air from the pipe 34 to

the interior of the air bag 25. The springs 21 and 14 are of such relative strength that the air pressure thus admitted to the air bag 25 first moves the two parts 10 and 11 relatively to each other about the hinges 13 to 70 cause the outer walls of the parts 10 and 11 to engage the walls of the mold firmly, and then the continued supply of air to the air- bag 25 forces the letter blocks 16 outward simultaneously to cause the letters 20 on the 75 type blocks 19 to embed themselves in the mold walls. The air pressure in the bag 25 is uniform throughout the bag, of course, so that the letter blocks 16 move radially, and so that the various letters are all embedded 80 to substantially the same depth. When the letters 20 have been pressed into the mold walls, the valve 33 is turned to allow the air in the air bag 25 to escape to the atmosphere through the exhaust L 35, whereupon the 85 springs 21 first force the letter blocks 16 radially inward and then the spring 14 pulls the two parts 10 and 11 together. Then the mold stamping machine may be withdrawn 90 from the mold, and the pipe cast in the mold 95 in the usual manner. Since the letters 20 are within the cylindrical outline of the machine, the letters do not drag against the mold wall when the machine is being inserted or withdrawn, and because of the relative strength of the springs 21 and 14 the movement of the letter blocks is always radial so as to produce perfectly legible letters. When the next pipe mold is ready, the 100 lettering on the mold stamping machine may be changed as desired and the operation repeated with such mold.

I claim as my invention:

1. A mold stamping machine, comprising a hollow body portion composed of a plurality of parts movable relatively to each other, a spring tending to draw said parts together, a letter block mounted in said body portion to slide inward and outward, a spring tending to draw said letter block inward, said last-named spring being stronger than said first-named spring, and means for applying fluid pressure within said body to move said body parts outward relatively to each other and to move said letter block outward relative to the body.

2. A mold stamping machine, comprising a hollow body portion, a letter block mounted in said body portion to slide inward and outward, a spring tending to draw said letter block inward, and means for applying fluid pressure within said body to move said letter block outward relative to the body.

3. A mold stamping machine, comprising a hollow body portion composed of a plurality of parts movable relatively to each other, a letter block mounted in said body portion to slide inward and outward, a spring tending to draw said letter block inward, and means for applying fluid pressure

within said body to move said body parts outward relatively to each other and to move said letter block outward relative to the body.

5 4. A mold stamping machine, comprising a hollow body portion, a letter block mounted in said body portion to slide inward and outward, a spring tending to draw said letter block inward, and means for applying 60 fluid pressure within said body to move said letter block outward relative to the body.

10 5. A mold stamping machine, comprising a hollow body portion, a letter block mounted in said body portion to slide inward and 65 outward, and means for applying fluid pressure within said body to move said letter block outward relative to the body.

15 6. A mold stamping machine, comprising a hollow body portion, a letter block mounted in said body portion to slide inward and outward, means for applying fluid pressure 70 within said body to move said letter block outward relative to the body, and type letters removably mounted in said letter block.

20 25 7. A mold stamping machine, comprising a hollow body portion comprising a plurality of relatively movable parts, a spring tending to draw said parts together, a letter block mounted in said body portion and 75 movable inward and outward relatively thereto, a spring tending to draw said letter block inward, said last-named spring being stronger than said first-named spring, an air bag of flexible material mounted within said 80 hollow body and bearing against said block, and means for supplying fluid pressure to the interior of said air bag for spreading the parts of the body part and for forcing said letter block outward.

30 35 40 45 8. A mold stamping machine, comprising a hollow body portion, a letter block mounted in said body portion and movable inward and outward relatively thereto, a spring tending to draw said letter block inward, 85 said last-named spring being stronger than said first-named spring, an air bag of flexible material mounted within said hollow body and bearing against said block, and means for supplying fluid pressure to the interior of said air bag for forcing said letter block outward.

50 55 9. A mold stamping machine, comprising a hollow body portion comprising a plurality of relatively movable parts, a letter block mounted in said body portion and movable

inward and outward relatively thereto, a spring tending to draw said letter block inward, an air bag of flexible material mounted within said hollow body and bearing against said block, and means for supplying 60 fluid pressure to the interior of said air bag for spreading the parts of the body part and for forcing said letter block outward.

10 15 20 25 10. A mold stamping machine, comprising a hollow body portion, a letter block mounted in said body portion and movable inward and outward relatively thereto, a spring tending to draw said letter block inward, an air bag of flexible material mounted within said hollow body and bearing 70 against said block, and means for supplying fluid pressure to the interior of said air bag for forcing said letter block outward.

30 35 40 45 11. A mold stamping machine, comprising a hollow body portion, a letter block mounted in said body portion and movable inward and outward relatively thereto, an air bag of flexible material mounted within said hollow body and bearing against said block, and means for supplying fluid pressure 75 to the interior of said air bag for forcing said letter block outward.

50 55 60 65 12. A mold stamping machine, comprising a hollow body portion comprising a plurality of relatively movable parts, a letter block mounted in said body portion and movable inward and outward relatively thereto, an air bag of flexible material mounted within said hollow body and bearing 80 against said block, and means for supplying fluid pressure to the interior of said air bag for spreading the parts of the body part and for forcing said letter block outward.

65 70 75 80 85 90 95 100 105 13. A mold stamping machine, comprising a hollow body portion, a letter block mounted in said body portion and movable inward and outward relatively thereto, an air bag of flexible material mounted within said hollow body and bearing against said block, means for supplying fluid pressure to the interior of said air bag for forcing said letter block outward, and type letters removably mounted in said letter block.

In witness whereof, I have hereunto set 105 my hand at Burlington, New Jersey, this thirty-first day of May, A. D. one thousand nine hundred and fifteen.

ALEXANDER T. DRYSDALE.
